ABSTRACT OF THE DISCLOSURE

System for controlling the pressure of steam introduced into a paper drying drum in such a way that the temperature of the paper web leaving the drum will be constant. This is accomplished by deriving a predictive feed-forward signal from consideration of a heat balance around the drum and by varying the predictive signal with a feedback signal proportional to actual exit temperature. The modified feed-forward signal is then used as an error signal for controlling the steam pressure within the drum, and, hence, its temperature.

BACKGROUND OF THE INVENTION

In the manufacture of paper from wood pulp, the pulp in a head box passes through a slice gap or slit onto a "wire" comprising a fine wire screen in the form of an endless belt, usually several feet wide. Vibration of the screen spreads the material in a thin uniform layer or web. As it is carried along on the wire, much of the water in the soft mass drains out. To prevent the material from running over the edges of the wire, rubber belts are usually placed on either side. Mechanical suction removes much of the water from the wet pulp mass, after which the web passes between rollers to a thick woolen felt which is carried between a series of heavy rollers. Passing between these, the paper is pressed into a firm thin sheet, and thereafter passes over a series of heated drying rolls. Usually, the web passes over the initial rolls while it is still on the felt mat; however, after sufficient drying has taken place, the web may be separated from the felt mat and passed over the remaining drying rolls to a sizing press without any external support.

The initial drying roll or rolls over which the web passes, are ordinarily referred to as the "pre-dryer." The main function of the pre-dryer is to heat the pulp web or sheet to a predetermined temperature. It has been found from actual operating experience that if the web, upon leaving the pre-dryer, is at a certain desired temperature (which in one case is 160° F.), then the remaining dryers can be operated much more efficiently. There is no theoretical justification for this; it is something that must be found out from experience.

Thus, it is of primary importance to hold the temperature of the sheet, as it emerges from the pre-dryer, at a constant, predetermined temperature. Introducing a set amount of steam into the pre-dryer drum or drums will not give a constant output temperature for the reason that the moisture content of the sheet, its density, its velocity, the amount of air blowing over the drum, and other factors will vary, meaning that the amount of heat and, hence, the amount of steam needed to maintain a fixed output temperature will vary. Furthermore, a system which attempts to control output temperature by measuring the temperature of the issuing web is highly unsatisfactory since, among other things, it constitutes control "after the fact" rather than "before the fact." That is, if an attempt is made to control the steam input to the drying drum as a function of exit temperature only, the

measuring instrument, which is spaced from the roll, will measure the temperature after the strip has traveled from the drum; but during this time the conditions of pulp consistency, velocity and the like may have changed entirely.

SUMMARY OF THE INVENTION

In accordance with the present invention, the temperature of pulp issuing from the pre-drying drum of a paper-making machine is controlled by conducting a heat balance around the drum to generate a feed-forward signal indicative of the pressure and temperature of the steam necessary to raise the temperature of the web from a known input temperature to a desired output temperature. This feed-forward signal is then modified by a feedback signal derived by comparison of desired output temperature with the actual output temperature of the web to derive an error signal for controlling the pressure of the steam in the drying drum.

The feed-forward signal is generated from a consideration of the fact that the heat, Q_2 , required to heat up the paper web from an incoming temperature, T_2 to an outgoing temperature, T_3 , equals the heat, Q_1 , transferred from the inside of the dryer drum or drums to the web. The heat, Q_1 , transferred from the inside of the drum to the web can be calculated from a consideration of the heat transfer characteristics of the drum, the temperature of the steam within the drum, and the sheet temperatures, T_2 and T_3 , at the input and output of the drying drum or drums, respectively. Q_2 , the heat required to heat up the paper web from temperature T_2 to temperature T_3 can be calculated from the mass flow rates of pulp and water flowing onto the drying drum, the specific heats of the fiber and water, and the temperatures T_2 and T_3 . Since Q_1 must always be equal to Q_2 , an equation can be derived for determining the temperature, T_p , of the steam. This temperature then comprises a feed-forward signal which is modified by a comparison of the desired output temperature with actual output temperature to vary the steam flow into the pre-dryer drum.

The above and other objects and features of the invention will become apparent from the following detailed description taken in connection with the accompanying single figure drawing which schematically illustrates one embodiment of the invention.

With reference now to the drawing, the embodiment of the invention shown includes a felt belt 10 which carries, on its upper surface, a moist web of pulp 12 which is to be dried and pressed into paper sheet. The felt, with the moist pulp thereon, passes over a pre-dryer 14 comprising a rotatable drum having a hollow interior into which steam from line 16 is introduced. The exhausted steam, in turn, passes out of the hollow interior of the drum 14 through conduit 18 to a condenser or separator 20.

As was mentioned above, the pre-dryer drum 14 is the first drying drum in the process of drying and rolling pulp into paper and may comprise a series of drums rather than the single drum shown herein. The drum normally comprises a cast iron cylinder with a wall thickness of about 1½ inches, the heat of the steam within the hollow interior of the drum being transferred through the wall of the drum to the felt 10 and pulp 12. In order to obtain maximum efficiency in subsequent drying operations, it is desired that the pulp issuing from the pre-dryer 14 have a predetermined temperature which, in one specific example, is 160° F.

The temperature of the pulp issuing from the pre-dryer is measured by a temperature measuring device 22 which produces an electrical signal on lead 24 proportional to that temperature. Similarly, the temperature of the incoming pulp is measured by a temperature meas-

uring device 26 which produces an electrical signal on lead 28 proportional to the measured temperature. In addition, the density of the pulp on felt 10 is measured and converted into a proportional electrical signal by a beta gauge 30. This electrical signal is multiplied by a constant, K_1 , at 32 to produce a signal M_{fib} which is proportional to the pounds of dry fiber pulp per minute passing along the felt belt 10. This, of course, assumes a constant speed of the belt 10. If the speed of the belt should vary, then a tachometer generator and compensating circuitry will have to be employed for variations in speed.

As was mentioned above, it is desired to maintain the output temperature, T_3 , at a desired specific value. Furthermore, the heat, Q_2 , required to heat up the pulp from the incoming temperature T_2 to the outgoing temperature T_3 equals the heat, Q_1 , transferred from the inside of the dryer drum to the web. Mathematically, this can be expressed as follows:

$$(1) \quad Q_1 = Q_2$$

and

$$(2) \quad Q_1 = (N \cdot U \cdot A) \cdot \frac{T_3^* - T_2}{\ln \frac{T_p^* - T_2}{T_p^* - T_3^*}}$$

where:

N =number of rolls in the pre-dryer (one in the example given);

U =overall heat transfer coefficient (B.t.u./° F.·ft.²·min.);

A =contact area of the sheet and roll (ft.²);

T_p^* =calculated desired temperature of steam in drum 14 (° F.);

T_2 =actual input temperature of pulp (° F.); and

T_3^* =desired output temperature of pulp (° F.).

Q_2 can be calculated from:

$$(3) \quad Q_2 = (M_w \cdot C_w + M_{fib} \cdot C_{fib}) \times (T_3^* - T_2)$$

where

M_w =moisture in incoming sheet (lbs./min.);

C_w =specific heat of water (B.t.u./lb.·° F.);

M_{fib} =bone dry pulp rate (lbs./min.); and

C_{fib} =specific heat of dry pulp (B.t.u./lb.·° F.).

From the relationship $Q_1 = Q_2$ follows:

(4)

$$N \cdot U \cdot A \cdot \frac{(T_3^* - T_2)}{\ln \left(\frac{T_p^* - T_2}{T_p^* - T_3^*} \right)} = (M_w \cdot C_w + M_{fib} \cdot C_{fib}) \cdot (T_3^* - T_2)$$

or

$$(5) \quad \frac{N \cdot U \cdot A}{M_w \cdot C_w + M_{fib} \cdot C_{fib}} = \ln \left(\frac{T_p^* - T_2}{T_p^* - T_3^*} \right)$$

Let:

$$(6) \quad C = N \cdot U \cdot A$$

Therefore:

$$(7) \quad \ln \left(\frac{T_p^* - T_2}{T_p^* - T_3^*} \right) = \frac{C}{M_w \cdot C_w + M_{fib} \cdot C_{fib}} = F$$

Or:

$$(8) \quad \frac{T_p^* - T_2}{T_p^* - T_3^*} = e^F$$

$$(9) \quad \frac{T_p^* - T_2}{e^F} = T_p^* - T_3^*$$

$$(10) \quad (T_p^* - T_2)e^{-F} + T_2 = T_p^* - T_3^* + T_2$$

$$(11) \quad -T_p^*e^{-F} + T_2e^{-F} - T_2 + T_p^* = T_3^* - T_2$$

$$(12) \quad -T_2(1 - e^{-F}) + T_p^*(1 - e^{-F}) = T_3^* - T_2$$

$$(13) \quad (T_p^* - T_2) = \frac{T_3^* - T_2}{1 - e^{-F}}$$

Or:

$$(14) \quad T_p^* = T_2 + \frac{T_3^* - T_2}{1 - e^{-F}}$$

Thus, the desired steam temperature T_p^* can be calculated from Equation 14; and this is performed in computer circuitry identified by the reference numeral 34 in the drawing to produce an electrical quantity comprising the feed-forward signal. The computer circuitry 34, as well as the other circuit blocks shown herein, may comprise part of a general purpose computer which is programmed to perform the calculation of Equation 14 and the other control functions described herein to produce an electrical quantity comprising the feed-forward signal.

However, it is shown as hard-wired logic in the drawing to facilitate explanation.

The quantity M_w is derived in block 36 by multiplying M_{fib} times a constant K . That is, it is assumed that a certain rate of dry pulp flowing to the drum 14 will contain a fixed percentage of water. The quantity T_3^* is entered into the computer circuitry 34 from block 38 and is selected by an operator.

Since the parameter to be controlled is the actual exit temperature T_3 , this temperature is compared with the desired temperature T_3^* , at 40 and the quotient or ratio subtracted from 1 in block 42 to derive a corrective feedback signal which is integrated in integrating controller 44 and multiplied with the quantity T_p^* at the output of circuit 34 at 46. This corrected value T_p^* is then applied to circuit 48 where it is multiplied by a factor f from a steam table 50 stored in the computer memory to derive P^* . P^* is the desired pressure of the steam within the drum 14 to achieve an exit temperature equal to T_3^* .

35 The actual steam fed into the drum 14 is controlled by means of valve 52 connected to a pressure controller 54 which receives a set point signal from integrating controller 56. The set point of controller 56, in turn, is derived by comparing in comparator 60 P^* from block 40 with the actual steam pressure P as derived from a pressure sensing device 58. Thus, a servo loop is established in which any change in the value of P^* will cause an adjustment in the setting of valve 52 which, in turn, will vary the output of pressure sensing device 58 until the two signals, P^* and P , are equal, at which time the pressure in the drum 14 is equal to the calculated desired pressure P^* .

In the foregoing Equation 2, the quantity U , the overall heat transfer coefficient, includes losses to the air blowing across the pulp and perhaps the tightness of the felt and other factors. For this reason, the quantity U is not a fixed value but changes and, consequently, it is desirable to update the quantity U . This is achieved by measuring the amount of condensate coming out of the dryer at 60 and converting this at 62 into the amount of heat actually given up by the steam by multiplying pounds of condensate by a constant K_2 . This, then, can be compared with calculated heat transferred, Q_1 , in circuitry 64 and the difference derived at 66 integrated at 68 and used to multiply U^* , the predicted heat transfer coefficient, at 70. This gives a corrected value of U which is fed back to circuit 34.

Although the invention has been shown in connection with a certain specific embodiment, it will be readily apparent to those skilled in the art that various changes in form and arrangement of parts may be made to suit requirements without departing from the spirit and scope of the invention.

We claim as our invention:

70 1. In papermaking apparatus of the type wherein a web of moist pulp is heated by passing it over a hollow drying drum charged with steam through a steam supply line having a control valve therein whereby the heat of the steam is transferred through the wall of the drum to the pulp, the improvement comprising a system for main-

taining the temperature of the pulp issuing from the drum at a preset value, said system including:

means for computing the desired temperature of the steam within said drum from a consideration of the heat required to heat up the pulp from a known input temperature to a desired output temperature and the heat transferred from the interior of the drum to the pulp, said means for computing the desired temperature of the steam within said drum including a device for measuring the actual temperature of pulp passing to the drying drum and means for determining the weight per unit of time of dry pulp and moisture passing to the drying drum,

means responsive to the desired steam temperature thus computed for generating a feed-forward error signal for controlling the admission of steam into said drum, means for comparing the actual output temperature of said pulp with said desired output temperature to derive a feedback error signal which modifies said feed-forward signal until the desired and actual temperatures are the same, and

valve control means responsive to said feed-forward signal as and if modified for controlling said control valve and, hence, the admission of steam into said drying drum.

2. The improvement of claim 1 wherein said computed desired temperature of the steam within said drum is compared with temperatures stored in a steam table to derive a feed-forward error signal proportional to the desired pressure of the steam within said drum.

3. The improvement of claim 1 wherein the means for computing the desired temperature of the steam within said drum computes said temperature from the equation:

$$T_p^* = T_2 + \frac{T_3^* - T_2}{1 - e^F}$$

where T_p^* is the desired temperature of the steam within said drum, T_2 is the temperature of the pulp passing to the drying drum; T_3^* is the desired output temperature

of the pulp as determined by an operator; N is the number of rolls over which the pulp passes, U is the overall heat transfer coefficient of the drying drum, A is the contact area of the pulp with the periphery of the drying drum, M_{fib} is the bone dry pulp rate, C_{fib} is the specific heat of the dry pulp, M_w is the moisture in the incoming sheet, and C_w is the specific heat of water and F is

$$\frac{N \cdot U \cdot A}{M_w \cdot C_w + M_{fib} \cdot C_{fib}}$$

10 4. The improvement of claim 3 wherein said means for computing the desired temperature T_p^* produces an electrical signal proportional to T_p^* and includes means for comparing an electrical signal proportional to T_3^* with an electrical signal T_3 , proportional to actual output temperature to derive an error signal for modifying the electrical signal proportional to T_p^* .

15 5. The improvement of claim 4 wherein said electrical signal proportional to T_p^* is compared with known information stored in a steam table for deriving an electrical signal proportional to P^* which is the desired pressure of the steam within said drying drum.
